UNITED STATES PATENT OFFICE.

SILAS MCCLURE AND STANLEY W. PALMER, OF MINNEAPOLIS, MINNESOTA; SAID PALMER ASSIGNOR TO SAID MCCLURE.

VALVE MECHANISM.

Application filed January 24, 1923. Serial No. 614,639.

To all whom it may concern:

Be it known that we, SILAS MCCLURE and STANLEY W. PALMER, citizens of the United States, residents of Minneapolis, in the 5 county of Hennepin and State of Minnesota, have invented certain new and useful Improvements in Valve Mechanisms, of which the following is a specification.

This invention relates to new and useful 10 improvements in valve mechanism and is more particularly directed to improvements in automatically controlled valves such, for example, as by means of changes in pressure or temperatures. In the embodiment of the 15 invention here shown, the improved valve mechanism is illustrated and described as being adapted to be automatically controlled by temperature fluctuations and the specific form of valve is adapted to control 20 the flow of gas to a common form of gas stove or range.

The object of the invention is to provide an improved valve mechanism.

A further object is to provide a compact 25 accurate gas-valve mechanism and one which can be easily and simply corrected or calibrated particularly without openings through which gas might eventually escape.

Other objects of the invention will more 30 fully appear from the following description and the accompanying drawings and will be pointed out in the annexed claims.

In the drawings there has been disclosed 35 a structure designed to carry out the objects of the invention but it is to be understood that the invention is not confined to the exact features shown as various changes may be made within the scope of the claims which follow.

In the drawings:

Figure 1 is a view in front elevation of a portion of a common form of gas range, the oven being partially broken away to show the thermostatic element;

Figure 2 is a vertical sectional view 45 through the gas range adjacent the oven wall and showing the oven in side elevation with the positioned thermostatic element shown in dotted lines;

Figure 3 is a view in plan of the novel 50 valve mechanism and its operative connection.

Figure 4 is a view in side elevation of the valve mechanism to illustrate the dial wheel and showing the calibrating disk in dotted 55 lines;

Figure 5 is a cross-sectional view through the valve and associated parts;

Figure 6 is a vertical sectional view on the line 6-6 of Figure 5;

Figure 7 is a vertical sectional view on the irregular line 7-7 of Figure 5;

Figure 8 is a vertical sectional view on the line 8-8 of Figure 5;

Figure 9 is a vertical sectional view on 65 the line 9-9 of Figure 5 and showing the detent and stop member;

Figure 10 is a detail view of the oven end of the thermostatic element, the tube being broken away to show a method of fixing the 70 end of the wire to the tube; and

Figure 11 is a perspective view of the calibrating disk.

The selected embodiment of this valve mechanism, which is shown for purposes of 75 explanation of the invention, is one adapted more specifically to control the flow of fuel gas to the ovens of any of the common forms of gas cooking stoves or ranges. But, obviously, the mechanism is broadly adapted to control fluid flow either in response to the temperature changes, as here shown, or in response to other conditions automatically effecting valve movement.

The valve mechanism includes a housing 85 11 having closures formed by the front plate 12 and the rear plate 13 secured to the housing by the screws 14. The enclosed valve compartment is divided into an inlet chamber 15 and an outlet chamber 16 by 90 means of a web 17 integral with the casting forming the housing. The valve seat is preferably annular in form and is provided by the web around a circular aperture which affords a passage 18 through the web. The valve 19 is formed by a substantially conical annular enlarged portion integrally provided upon the exterior of a sleeve 21 which functions substantially as a valve stem to carry the valve. Rearwardly, this sleeve 21 95 is slidably received within a recessed boss 22 inwardly projecting from the rear plate 13. This boss provides a running and guiding fit for the rear end of the sleeve. The front 100

end of this valve sleeve is preferably provided with a resilient mounting so that the valve may normally be held to its seat to cut off the flow of fuel gas through the valve structure.

The front plate 12 is provided with a tapered aperture to receive the tapered block 23. The inner end of this block is counterbored to provide annular walls 24 and 25 which are formed with diametrically aligned slots to receive similarly aligned tongues 26 terminally formed on the valve stem sleeve. This tongue-and-slot connection between the block (which is held in relatively fixed position) and the valve sleeve permits slidable or longitudinal movement of the valve sleeve but holds the sleeve against rotation. The periphery of the annular walls 24 and 25 are threaded adjacent their inner ends in order to receive the nut 27 in adjustable threaded engagement thereon. The opposite faces of this nut are preferably flattened as is shown in Figure 8 in order to facilitate adjustment of the nut. A washer 28 is positioned upon the inner face of the nut 27 and functions to hold the compression spring 29, coiled about the sleeve 21, against the face of the shoulder outwardly presented by the enlarged portion 30 which forms the valve 19. This compression spring yieldably holds the valve in normal seated position.

Tension means are also provided inwardly to pull the block so that it is maintained in position against the inner face of its tapered aperture in the front plate so that a gas-tight union is provided. Such is the purpose of the compression spring 31 coiled about the inner end portion of the block 23 and held between the washer 32 and the washer 33 seated upon the inner face of the front plate 12.

Means are provided in connection with this novel valve structure whereby the movement of the valve toward or from seated position may be controlled in response to predetermined conditions. Furthermore, means are also provided for the adjustment of the connection of such a controlling means with the valve so that the controlling function may be varied. And a still further major improvement resides in the provision of means for calibrating the mechanism so that correct indication of the adjustments of the mechanism may be indicated.

In this embodiment of the invention such controlling means are shown as thermostatic in nature and as functioning in response to changes in temperature. The specific form 60 of thermostatic element here shown forms the subject-matter of another co-pending application by one of the joint inventors hereof and need not therefore be described in detail. Broadly, it consists of a metallic tube 34 having one end fixed to the valve

housing. A form of such connection is shown in Figure 5 wherein one end of the tube is outwardly flared in order to be positioned upon a conical seat rearwardly presented by the counterbored boss 36 projecting from the outer face of the rear plate 13. A nut 37, having a hollow interior to receive the tube and sleeve, is held in adjusted threaded engagement with the boss and abuts against the flared end of the tube to maintain such end of the tube in fixed position. In Figures 1 and 2, the tube 34, extending from the valve housing, is shown as passed through the outer wall 38 of a common form of gas range oven and upwardly into the usual space provided between the lining 39 and the usual oven wall 40 of the oven. The tube is curved into substantially circular form and is slidably supported by a bracket 41 mounted upon the lining 39 of the oven.

A wire 43, which is of flexible material having a different coefficient of expansion from that of the tube, extends longitudinally through the tube. The wire is fixed to the tube at the free or oven end of the tube and freely projects from the fixed or valve end of the tube. The preferred materials for the tube and wire are brass and steel respectively, the brass having a relatively high coefficient of expansion while the steel has a relatively low one. However, an alloy of steel having a low coefficient of expansion coupled with non-corrosive attributes may be employed as the wire-material. A convenient form of fixing the end of the wire to the free end of the tube 34 is shown in Figure 10 wherein the end of the wire is shown as upset tightly to fill the tube while a metallic collar 42 is shrunk on the tube and the wire, tube and collar are brazed so that relative movement of the tube and wire are effectually prevented at this end and a gas-tight union is had. Hence, changes in temperature to which the tube and wire are subjected within the oven must result in the increased or decreased projection of the free end of the wire from the fixed valve end of the tube. The free end portion 44 of the wire, projecting from the tube is adapted to be seated within a recess rearwardly presented by the shaft 45 which is exteriorly threaded and held in threaded engagement within the valve stem sleeve 21. The shaft is held against the free end of the thermostatic wire by the valve spring 29.

In the position of the parts shown in Figure 5, the tube 34 is in a contracted position with the result that the wire 43 is projected therefrom sufficiently to push the valve sleeve forwardly by means of the shaft 45, to hold the valve 19 in an open position against the tension of the spring 29, thus permitting flow of gaseous fuel. As the oven attains the temperature for which the

mechanism has been set, the tube will be expanding sufficiently to draw progressively the free end of the wire away from the shaft 45 so that the valve, under tension of its 5 spring, will follow the wire rearwardly and gradually reduce the flow of gas through the valve passage 18. The accuracy and sensitiveness of this mechanism is such that the valve does not appreciably lag in assuming different positions responsive to temperature changes in the oven so that the flow of gas is constantly controlled and overrunning of the predetermined temperature in the oven is effectually prevented.

15 Means are provided for the adjustment of the connection between the thermostatic wire and the valve structure so that the mechanism may be set to control the flow of gas in order to bring the oven temperature to, and maintain it at, a predetermined degree. Adjustment of the cylindrical shaft 45 within the valve stem sleeve 21 functions 20 to move the sleeve and valve 19 relatively to the shaft. Because the shaft is tensionably held against the free end of the thermo-wire 43, rotation of the thus-held shaft will cause the non-rotatable sleeve to assume a longitudinally variant position on 25 the shaft and thus relatively move the valve closer to or away from its seat.

The externally tapered block 23 is provided with a central tapered aperture to receive the similarly tapered plug 46 inwardly terminating in a tongue 47. This 30 tongue is adapted to be slidably, but non-rotatably, received within an elongated recess in the forward end of the adjusting shaft 45. The front portion of this tapered plug 46 is threaded to receive the nut 48. A compression spring 49 is coiled about this 40 plug portion and held between the nut 48 and the block so that the tapered plug is firmly held in a gas-tight seated position which permits rotation of the plug relatively to the block without the necessity for stuffing-boxes, gaskets, etc. The adjustment of the position of the valve relatively to the shaft may conveniently be effected by 45 means of an indicator wheel 51 having a flange 52 upon which are placed temperature indications in degrees running from minimum to maximum over the desired range which in this use of the mechanism may be from 150 degrees to 550 degrees 50 Fahrenheit. The wheel 51 is mounted upon the plug 46 to rotate therewith and for this purpose the wheel is formed with a central aperture which is circular except for one flattened or chord-like portion to fit upon a complementarily formed terminal portion 55 of the plug as shown in dotted lines in Figure 4. The advantage of having only one side of the wheel aperture and plug flattened is that the wheel can only be mounted or replaced in correct position.

The screw 54 is received in threaded engagement within the end of the plug and demountably retains the wheel in its operative position. A score-mark, such as an arrow 55, may be placed upon the upper 70 margin of the front plate 12 to co-operate with the wheel indications. Thus, by means of the co-operable front plate score-mark and the various wheel indications, the wheel may be turned by the user to a definite position so that the valve and thermostatic element may function to control the flow of gas to bring the oven temperature to, and thereafter maintain it at, a predetermined degree.

80 Means are provided to prevent more than a complete rotation of the dial wheel. Obviously, if the user were able to turn the wheel more than one revolution, and in doing so forgot to turn it back correctly, 85 the sleeve and shaft would be misplaced with reference to the co-operative scale indications and the score-mark so that the device would not accurately function. Such occurrence is prevented by the employment 90 of a detent co-operable with a fixed part of the valve housing. The detent-pin 56 is fixed to the enlarged rear end of the shaft 45 in a position so that its arcuate path is intercepted by a boss 5 forwardly projecting 95 from the inner face of the rear plate 13. The pin 56 and its stopping boss 5 are so arranged that the dial wheel rotation is stopped from movement at a point beyond the maximum degree mark and below the 100 minimum degree mark. This arrangement prevents the device from being regulated to a too-great heat or to a too-low heat, as well as preventing derangement of co-operable adjustment of the valve and shaft 105 with relation to the dial wheel and its fixed score-mark. Thus, the few parts of this valve mechanism are such as to permit accurate fitting and assembly at the factory so that the mechanism may be quickly installed in 110 a range. In use, the rotation of the wheel so that the desired degree notation is opposite the score-mark, causes the rotation of the adjusting shaft 45 with relation to its threaded valve-carrying sleeve 21. The 115 sleeve, while permitted longitudinal movement, is held against rotation by its tongue-and-slot connection with the stationary block 23. Thus rotation of the wheel and shaft changes the relative positions of the 120 valve 19 and shaft so that flow of gas past the valve may be changed while the shaft occupies the same position. For example, assume the oven temperature in the position of the mechanism shown in Fig. 5 is 250 125 deg. F. and it be desired to raise the oven temperature to 350 deg. F. The user turns the dial wheel in a clockwise direction until the 350 deg. F. notation on the wheel is opposite the arrow on the front plate. Thus, 130

the shaft, which is constantly held in abutting relation with the thermo-wire 43, does not move longitudinally, but does rotate with the wheel and therefore the sleeve 5 (which cannot rotate) is moved longitudinally toward the wheel or forwardly. Such forward movement of the wheel moves the conical valve 19 further away from its seat and permits the increased flow of gas to 10 the oven burner whereby the oven temperature is increased. As the oven temperature is increased toward the desired degree, the tube 34 and thermo-wire 43 are correspondingly heated and the differential of expansion 15 draws the terminal portion 44 of the wire rearwardly so that the valve tensionably moves rearwardly to reduce the flow of gas. Movement of the wheel by the user in a counter-clockwise direction correspondingly moves the valve sleeve rearwardly 20 with relation to the regulating shaft 45 so that a lessened flow of gas for the same wire and shaft position results.

A feature of major importance in this 25 novel invention consists in the provision of an improved means of calibration. That is, if for any reason the setting of the mechanism for the attainment of the desired oven temperature does not result in the maintenance 30 of the corresponding actual oven temperature, then the indicating mechanism may be re-set. This mechanism may be re-set or calibrated by a few simple adjustments which may be made without necessity 35 of shutting off the flow of gas thereto or danger of leakage.

This calibration is effected by regulating the normally operative position of the valve-carrying sleeve 21 with relation to the shaft. 40 This is conveniently done by rotation of the block 23 which occupies a normally fixed position. The calibrating disk 10 shown in Figure 11 has a central aperture which is circular except for a straight portion in the 45 direction of a chord. This disk is positioned upon the complementarily formed shoulder on the front end of the block 23. Such conformation assures the accurate assembly of the disk and block. The set-screw 20 is received in threaded engagement in the 50 front plate 12 and its head overhangs the peripheral portion of the disk to hold the disk and block in a normally fixed relation to the housing and yet permit adjustment of the disk by partial or complete rotation as 55 necessary. Preferably a spacing washer 30 is carried by the set screw between the front plate and disk. By such construction, this calibrating disk is concealed during all normal 60 operation of the mechanism. Furthermore, the tongue-and-slot connection of the block and sleeve permits this longitudinal and rotatable calibrating movement in the same manner that the similar kind of connection between the plug 46 and regulating 65

shaft 45 permits the normal setting changes by the dial wheel. The disk may be graduated by radial lines which may be equivalent to five or ten degree marks upon the wheel. A simple means for turning the disk 70 is provided by the spaced opposed tabs 50 stamped from the metal of the disk. A device such as a screw-driver may have its end inserted between the radially aligned sets of tabs and the disk thereby turned clockwise 75 or counter-clockwise as necessary for re-setting. Access is afforded to the calibrating disk by removal of the screw 54 and demounting of the indicator wheel 51. A guide or zero mark is provided by an arrow 80 9 placed upon the front plate 12 adjacent the disk. This arrow is useful in indicating movement of the disk during calibrating.

In describing the calibration of this mechanism, it may be assumed that there is a discrepancy 85 between the oven temperature and that for which the wheel 51 has been set. Such discrepancy may be accurately determined by placing a Fahrenheit thermometer within the oven, taking such reading and by 90 comparison with the wheel indication, the number of degrees Fahrenheit of variation may be determined. Assume that the actual oven temperature is too low by α degrees. The indicator wheel is then turned counter-clockwise beyond the minimum scale marks until the shaft detent pin 56 strikes the boss 5. Holding the wheel in such position, the screw 54 is removed, and the wheel demounted. The disk set-screw 20 may then be loosened by a screw-driver and the end of the screw-driver inserted in the aligned tabs and the calibrating disk turned counter-clockwise α degrees with relation to the arrow 9. The set-screw 20 may then be tightened to 105 hold the disk in such calibrated position and the wheel thereafter restored to assembled position. In the event, the thermometer test showed the actual oven temperature too high, then the same steps are followed except that the wheel is turned to its limit of travel in a clockwise direction and the calibrating disk is also turned clockwise through the necessary number of degrees with relation to its fixed arrow 9.

This novel valve structure is particularly useful in connection with gas heated ovens because of its compact design. The present structures used for such purpose are relatively large, unwieldy and expensive, not 110 only increasing the amount of kitchen space necessary but also entailing increased difficulty of crating and shipping and liability to damage. Furthermore, the present devices whether applied to the side or front of the 115 ovens require special piping of the gas from the burner manifold and the regulating valve is located at a distance from the usual mixing chamber of the oven burner. This latter disadvantage increases the difficulty 120

of controlling the gas volume to desired low oven temperature because the gas must be piped from the burner manifold to the regulating device and then the regulated flow is carried through a relatively long passage to the mixing chamber.

This novel valve mechanism may be carried at the end of the usual burner manifold adjacent the mixing chamber or mixer 10 of the oven burner. In the drawings there is shown the usual burner manifold 57, which supplies gas to the usual cooking burner mixers 58. The novel valve housing 11 is formed with an integral head 59 having a threaded recess 61 to receive the threaded end of the manifold 57. The inner longitudinal side of this housing head 59 is bored to provide a gas conduit 62 leading from the recess 61 to the integral 20 nipple 63 adapted to receive in threaded engagement the usual nozzle 64, projecting into the usual oven burner mixer 70. A tapered aperture is transversely bored through the housing to intersect the conduit 25 62 and the similarly tapered valve plug 65 is seated therein and held in a gas-tight position by means of the compression spring 66 held between the housing and the nuts 67 terminally borne by the plug. 30 The valve plug is transversely bored to form a duct 68, adapted upon turning of the plug by its handle 69, to be in alignment with the conduit 62 affording unimpeded flow of gas from the recess 61 to the 35 oven burner mixer 70. This plug is also cut away upon one side to provide a pass 71 when in the position shown in Figure 5 so that the gas may freely pass from the supply side of the conduit 62 to the inlet port 72 leading through the housing casting to the inlet chamber 15. The outlet chamber 16, upon the other side of the valve seat, has an outlet port 73 leading to the delivery side of the conduit. Hence, 40 when the manually operable valve plug is in the position shown in Figures 5 and 6, the flow of gas from the manifold to the oven burner is controlled by the thermostatic device. It is preferable to provide 45 a by-pass around the automatically controlled valve in order that sufficient gas may be supplied as a pilot-light to the oven burner during automatic control to prevent failure of ignition. Such a by-pass is provided by the duct 74. The flow 50 through this by-pass may be regulated by the needle valve 75 received in adjustable threaded engagement within the threaded boring 76 which intersects the by-pass duct 74 so that graduated flow may be had or flow entirely stopped.

It will be noted that this particular mechanism is shown as adapted for use with what may be termed a left-hand oven, i. e., 55 a stove in which the oven is placed at the

left of the usual cooking burners. The mechanism may be easily changed for a right-hand oven. In such case, the boring for the by-pass needle valve may be oppositely formed and the valve placed in reversed positions as is indicated by the dotted lines of the slotted end of the stem as shown in Figure 7. Likewise, the manually operable valve may have its aperture reversely tapered and the plug may be reversely positioned as is indicated by the dotted-line showing of its handle in Figure 6. In making such change, the chord-side of the circular opening in the indicator wheel must be diametrically opposite. This is preferably done by initially stamping out such wheels for left or right use, and finally the arrow 55 may be repeated on the diametrically opposite side of the margin of the front plate 12 so that when the housing is turned through a semi-circle for connection with the left side manifold, the other arrow will be upwardly presented.

When the valve handle is in the position shown in Figures 3 and 6, the valve plug 65 is turned to provide the automatic thermostatic control of the oven burner. The handle 69, when turned to the median dotted line position shown in Figure 5, cuts off completely the supply of gas through the conduit 62. Such is the full-line position of the handle 69 shown in Figure 1. The handle 69 may also be turned to the upper dotted line position shown in Figure 5 whereat the duct 68 is in alignment with the conduit 62 and full flow of gas is afforded to the oven burner and the port 72 to the automatic control is cut off. Preferably, a detent pin 77 is provided to project from the housing as is shown in Figure 3 to prevent the handle from being normally turnable to such manually controlled position. However, this pin is demountable to provide such control to the exclusion of the automatic. A pin 78 projects from the exterior of the valve plug 65 and is adapted to abut against a shoulder upon the exterior of the housing as is shown in Figure 3 in order to arrest the plug so that the pass 71 may properly direct the gas to the inlet port leading to the inlet chamber.

Having thus described our invention, what we claim as new and desire to secure by Letters-Patent, is:

1. In a valve mechanism, the combination of a valve housing, a valve seat therein, a regulating member, a valve adjustably connected to the member and co-operable with the valve seat, indicating means connected to the member to regulate the position of the member and valve, and means to adjust the position of the valve with relation to the member whereby the mechanism may be calibrated.

2. In a valve mechanism, the combination

of a valve housing, a valve seat therein, a regulating shaft, a valve adjustably connected to the shaft and co-operable with the valve seat, indicating means connected to the shaft to regulate the position of the shaft and valve, and means to adjust the position of the valve with relation to the shaft whereby the mechanism may be calibrated.

10 3. In a valve mechanism, the combination of a valve housing, a thermostatic element, a valve, a regulating member having rotatably adjustable engagement with the valve and arranged to be controlled by the thermostatic element, means connected to said member normally to regulate valve-position, and means normally preventing rotation of the valve but operable to permit valve-rotation to change the adjustable engagement of 20 the member and valve whereby the mechanism may be calibrated.

4. In a valve mechanism, the combination of a valve housing, a thermostatic element having its free end extending within the housing, a valve, a regulating member having rotatably adjustable engagement with the valve, tension means yieldably to urge the valve toward seated position and to hold the regulating member against the free end 30 of the element whereby the position of the member and valve is controlled by the element, means connected to the member normally to regulate valve-position, and means normally preventing rotation of the valve 35 but operable to permit valve-rotation to change the adjustable engagement of the member and valve whereby the mechanism may be calibrated.

5. In a valve mechanism, the combination 40 of a valve housing, a thermostatic element, a valve, a regulating member having rotatably adjustable engagement with the valve and arranged to be controlled by the thermostatic element, means connected to the member 45 normally to regulate valve-position, and locking means connected to the valve to prevent rotation thereof, said locking means being releasable and adapted to rotate the valve to adjust its normal operable relation 50 to the regulating member whereby the mechanism may be calibrated.

6. In a valve mechanism, the combination 55 of a valve housing, a thermostatic element, a valve, a regulating member having rotatably adjustable engagement with the valve and arranged to be controlled by the thermostatic element, means connected to the member normally to regulate valve-position, locking means connected to the valve to prevent rotation thereof, said locking means being releasable and adapted to rotate the valve to adjust its normal operable relation 60 to the regulating member whereby the mechanism may be calibrated, and co-operable 65 indicia on said locking means and housing

to indicate amount of calibrating adjustment.

7. In a valve mechanism, the combination of a valve housing, a thermostatic element, a valve, a regulating shaft having rotatably adjustable engagement with the valve and arranged to be controlled by the thermostatic element, a shaft-controlling member extending through the housing and borne thereby to permit rotatable but not longitudinal movement, said controlling member being connected to the shaft to rotate the same and to permit relative longitudinal movement thereof by the element, and means to prevent valve-rotation whereby rotation of said controlling member may regulate valve-position.

8. In a valve mechanism, the combination of a valve housing, a thermostatic element, a regulating shaft adapted to have its longitudinal position controlled by the thermostatic element, a valve normally movable with the shaft and having a rotatably adjustable engagement therewith, means adapted to prevent valve-rotation, a shaft-controlling member rotatably borne by the housing and extending therethrough, said member being connected to the shaft to permit longitudinal movement thereof and to rotate the same with relation to the valve, and means on the exterior portion of said controlling member to rotate the same whereby valve-position may be regulated.

9. In a valve mechanism, the combination 100 of a valve housing, a thermostatic element, a valve, a regulating shaft having rotatably adjustable engagement with the valve and arranged to be controlled by the thermostatic element, means connectible to said shaft normally to regulate valve-position, valve-engaging means extending through the housing and borne thereby to permit rotatable but not longitudinal movement, said valve-engaging means being adapted to permit relative longitudinal movement of 110 the valve but to prevent relative rotation thereof, and means normally to lock said valve-engaging means in fixed position, said locking means being releasable whereby the valve may be rotated relatively to the shaft 115 to calibrate the mechanism.

10. In a valve mechanism, the combination 120 of a valve housing, a thermostatic element, a valve, a regulating shaft having rotatably adjustable engagement with the valve and arranged to be controlled by the thermostatic element, a shaft-controlling member extending through the housing and borne thereby to permit rotatable but not longitudinal movement said controlling member being connected to the shaft to rotate the same and to permit relative longitudinal movement thereof by the element, valve-engaging means also extending through the housing and borne thereby to permit rotat- 125 130

able but not longitudinal movement, said valve-engaging means being adapted to permit relative longitudinal movement of the valve but to prevent relative rotation thereof, and means normally to lock said valve-engaging means in fixed position, said locking means being releasable whereby the valve

may be rotated relatively to the shaft to calibrate the mechanism.

In witness whereof, we have hereunto set our hands this twentieth day of January, 1923.

SILAS McCLURE.

STANLEY W. PALMER.
